CLAIM

The ornamental design for a container with closure, as
shown and described.

DESCRIPTION

FIG. 1 is a perspective view of a container with closure
showing my new design;

FIG. 2 is a perspective view of a closure thereof;

FIG. 3 is a top plan view of FIG. 2;

FIG. 4 is a perspective view of a container thereof; and

FIG. 5 is a top plan view of FIG. 4 thereof.

The bottom of the container is plain and unornamented.

FIG. 1.

FIG. 2.***FIG. 3.*****FIG. 4.****FIG. 5.**
